DERRICK

James O. Presley and John A. Presley,
Wichita Falls, Tex.

Application April 15, 1936, Serial No. 74,528

1 Claim. (Cl. 189—16)

The present invention relates to new and useful improvements in derricks for use particularly in oil fields and has for its primary object to provide, in a manner as hereinafter set forth, a novel construction and arrangement through the medium of which the derrick may be expeditiously erected with a minimum of labor.

Other objects of the invention are to provide a derrick of the aforementioned character which will be comparatively simple in construction, strong, durable, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

20 Figure 1 is a view in side elevation, showing the derrick before it is erected.

Figure 2 is a view in side elevation, showing the derrick erected with parts broken away in vertical section.

25 Figure 3 is a view in front elevation of the lower portion of the invention.

Figure 4 is a view in front elevation of the upper portion of the invention.

Figure 5 is a view in rear elevation of the lower portion of the invention.

Referring now to the drawings in detail, it will be seen that the embodiment of the invention which has been illustrated comprises a base 1 of suitable material having an inclined or beveled forward end 2. The reference numeral 3 designates a tapered inner frame of suitable material which is pivotally mounted on the rear end portion of the base 1, as at 4.

The reference numeral 5 designates a tapered outer frame having fixed on its narrow inner end an angularly extending frame 6 to which the free end of the frame 3 is pivotally connected, as at 7. Journaled in the frame 6 is a pulley 8. Pivotally mounted on the free outer or lower end of the frame 5 are shoes 9. The frames 3 and 5 include suitable braces or struts 10.

A snatch block 11 is secured by a bridle 21 to the free end portion of the frame 5. Pulleys 12, 13 and 14 are journaled in the frame 3 adjacent the free end portion thereof. Journaled on the base 1 adjacent the pivoted end of the frame 3 is a drum 15 which may be actuated by suitable means, such as a hand crank 16. A cable 17 has one end secured to the drum 15 for winding thereon. The reference numeral

18 designates a mast or gin pole constituting an important part of the apparatus for raising the derrick. A pulley 19 is journaled on the upper end of the gin pole 18. From the drum 15, the cable 17 extends around the snatch block 11, then over the pulley 12, then under the pulley 13, then up and over the pulley 19 on the gin pole 18, and then under the pulley 14 and has its other end anchored to the base 1, as at 20. It will be observed that the gin pole 18 is located between the pulleys 13 and 14 when the derrick is to be erected.

It is thought that the operation of the invention will be readily apparent from a consideration of the foregoing. The apparatus is disposed substantially as shown in Figure 1 of the drawings at the site where it is to be erected. With the gin pole 18 in position between the rollers 13 and 14 and the cable 17 trained over the pulley 19 on said gin pole, the drum 15 is actuated in a direction to wind said cable thereon. The gin pole 18 functions to "break" or "jack knife" the sections 3 and 5 at the hinged joint therebetween, as suggested in dotted lines in Figure 1 of the drawings. After this has been done the cable 17 draws the free or lower end of the frame 5 toward the pivoted end of the frame 3, the shoes 9 riding up the inclined end portion 2 until said frame 5 rests on the base 1, as best seen in Figure 2 of the drawings. The derrick is now ready for use.

It is believed that the many advantages of a derrick constructed in accordance with the present invention will be readily understood, and although a preferred embodiment of the apparatus is as illustrated and described, it is to be understood that changes in the details of construction and in the combination and arrangement of parts may be resorted to which will fall within the scope of the invention as claimed.

What is claimed is:—

A derrick comprising, in combination, a base including an inclined end portion, a frame pivotally connected at one end to said base, a drum mounted on the base, a second frame, angularly extending members fixed on one end of the second-named frame and pivotally connected to the other end of the first-named frame, pivotally mounted ground engaging shoes on the other end of the second-named frame, a plurality of pulleys journaled on the first-named frame adjacent the said other end thereof, a pulley journaled on the second-named frame adjacent said other end thereof, a gin pole, a pulley journaled on the upper end of said gin pole, and a cable

having one end anchored to the base and its other end secured to the drum for winding thereon, said cable being trained over the pulleys for drawing said other end of the second-named frame toward said one end of the first-named frame for elevating the pivotally connected inner

ends of the frames when said cable is wound on the drum, the second-named frame resting on the base when in substantially vertical position.

JAMES O. PRESLEY. 5
JOHN A. PRESLEY.
